UNITED STATES PATENT OFFICE

SAMUEL NEWTON HOPE, OF WAUWATOSA, WISCONSIN, AND JOHN J. NEITZ, OF NAPERVILLE, ILLINOIS, ASSIGNORS TO DUDLEY LOCK CORPORATION, OF CHICAGO, ILLINOIS, A CORPORATION OF ILLINOIS

COMBINATION LOCK

Application filed February 27, 1929. Serial No. 343,034.

The present invention pertains to locks, and more particularly to locks of the permutation or keyless type, especially adapted for use in connection with various types of closures, such as lockers, wall safes and the like. More specifically the invention resides in the provision of certain novel and useful improvements in locks of this general character, and has for a primary object to produce an improved lock that is simple, strong and durable in construction, and capable of economical manufacture. Another object is to provide improved means for adjusting the graduated dial for varying the combination of the lock. A further object is to provide means, operable independently of the means for adjusting the tumblers, for actuating the lock bolt when the tumblers have been set in combination. It consists in certain features and elements of construction, in combination, as herein shown and described, and as indicated by the claims.

In the drawings:

Figure 1 is a face view in elevation of the lock embodying this invention shown applied to a panel type of closure member.

Figure 2 is an edge view in elevation.

Figure 3 is a vertical axial section, taken as indicated at line 3—3 on Figure 1.

Figure 4 is a rear view with the back plate of the lock casing removed, showing the mechanism adjusted ready for retraction of the lock bolt.

Figure 5 is a view similar to Figure 4, showing the mechanism in unlocked position.

Figure 6 is an enlarged fragmentary axial section showing details of construction.

Figure 7 is a transverse section through the operating knobs, taken as indicated at line 7—7 on Figure 3.

Figure 8 is a perspective view of the casing with the back plate removed.

Figure 9 is a perspective view of the lock bolt.

Figure 10 is a perspective axial disassembly of the rotating elements of the lock.

Figure 11 is a perspective view of the casing back plate.

As illustrated in the drawings the lock is shown affixed to the rear or inner side of a

panel, 10, which may be understood to be either a movable closure member or a cooperating panel adjacent the movable member, for closures such as lockers, vaults, etc. The lock comprises a casing, 11, of rectangular form, provided with a removable back plate, 12, and a front plate, 13, rigidly secured thereto and having outwardly projecting lugs, 14, at top and bottom which are secured to the panel, 10, by button-head bolts, 15; said bolts being arranged with their heads exposed to the outside of the panel and with the nuts, 16, on the inside of the panel to preclude removal of, or tampering with the lock from the exterior. If desired this front plate may be fabricated as an integral part of the casing, and as shown, said front plate is formed with an outwardly extending annular flange or sleeve, 17, adapted to be projected through an aperture in said panel and serve as a bearing in which is journaled a rotatable member serving as a tumbler actuating knob, 18.

Said knob is of hollow thimble formation having its inner end provided with a transverse flange, 21, adapted to abut against the inner side of said front plate, thus locking the thimble, 18, in the casing against withdrawal in an outward direction. Loosely circumscribing the sleeve, 17, and rotatable with the knob, is an annular indicator member, 22, provided with an outwardly flared skirt flange, 23, adapted to be seated against the outer surface of the panel 10. Said indicator is provided with an inwardly extending lug or key, 24, adapted to be slidably entered in a cooperating longitudinal groove, 25, formed in the wall of the hollow knob, 18, by means of which connection the indicator is caused to be rotated in either direction with said knob. A radially extending pointer, 26, is formed above said skirt flange, adapted to be registered or aligned with the graduation of a dial plate, 27, disposed concentrically with respect to the axis of rotation of the knob. Said dial plate is mounted to overlap the skirted flange of the indicator for holding the latter captive against axial shifting on the knob, but permitting rotary driving engagement therewith at all times. The dial

plate is formed with an axial offset flange, 28, at its peripheral edge, adapted to abut against the exterior surface of the panel 10 and is held captive by an escutcheon plate 29 which overlaps this offset flange and is secured to the panel by the bolts 15.

The peripheral flange, 28, of the dial plate which underlies the escutcheon plate is formed with radially extending grooves or corrugations, 30, preferably of V-shape in cross section. Not necessarily, but desirably there are the same number of grooves as there are graduations, with a groove aligned with each graduation on the dial plate. Formed in said escutcheon plate 29, at any convenient point within the area of the corrugated flange 28, herein shown at upper central position, is an inwardly extending node or depression, 32, adapted to register with one of the grooves 30 for firmly securing the dial plate in a fixed position of adjustment. It will now be apparent that the combination of the lock may be quickly and easily changed, by merely loosening bolts 15 to realign a different groove with the node 32, shifting the zero or starting point to a new position. Hence, by noting the number of units or graduations that the dial has been shifted, a corresponding number of units of rotation of the knob may be added or subtracted respectively to the previous combination for ascertaining the new combination. This feature of construction is especially desirable in locks of this type when applied to lockers for schools, clubs, etc. Where the locker is used for a season or certain period of time and then reassigned, (frequently to different individuals,) and in order to prevent unauthorized access to a locker by the person formerly occupying it, the combination is usually changed each time the locker is assigned to a new individual. In prior constructions, the alteration of a combination necessitated complete disassembly of the lock and relocation of certain of the interengaging members of the tumblers, which requires considerable time.

Disposed concentrically in and rotatable independently of the tumbler actuating knob 18 is a spindle 35 extending into the casing, having its inner end formed with a bore 36 adapted to be loosely journaled on a trunion or stud 37 secured to the inner wall of the back plate 12. The other end of the spindle 35 is supported in central position in the outer end of the knob, 18, and in an inwardly offset disk 38 rigidly secured inside the knob adjacent the inner end: the outer end of the spindle is provided with a knob, 39, projecting axially beyond said knob, 18, for manipulation of said spindle.

Slidably supported in the casing is a laterally shiftable lock bolt, 41, whose movement is controlled by the usual series of disk type tumblers, 42, loosely mounted on the spindle; notches 43 opening at the periphery and

adapted to receive the cooperating projections 44 of the lock bolt, when said notches are aligned by the setting of the tumblers in a predetermined arrangement or combination to permit free movement of the lock bolt into and out of locking position. The tumblers are axially separated on the spindle by horse-shoe shaped spacers, 45, which are anchored on a pair of studs, 46, extending inwardly from the front side of the casing; these studs serve to support the spacers in central relation to the spindle and insure freedom of operation of the interengaging or driving lugs, 47, on the respective tumblers, by means of which lugs the tumblers may be moved to their predetermined lock bolt releasing position, by the rotation of the master tumbler first in one direction and then in the other, as is well understood in the art.

Rigidly secured in the inner end of said knob 18 is a disk, 49, having a notch or slot, 50, which constantly engages the driving lug 47 of the first tumbler 42. A coil spring, 51, loosely carried on the spindle and interposed between the inner disk, 38 and the first, or master, tumbler, as shown in Figure 6, provides friction between the tumblers and spacers which tends to hold the tumblers in the positions at which they are adjusted in setting the combination, and also keeps them in their proper planes to insure engagement of their driving lugs 45 by which motion is imparted to the successive tumblers for adjusting them to position.

The inner end of the spindle is provided with a reduced portion, 55, forming a transverse shoulder, 56, against which is mounted a bearing washer, 57, and outside of the washer is a radially extending arm, 58, rigidly mounted on said reduced portion, by riveting over the end thereof. The outer end of said arm is slidably engaged in a recess, 59, formed in the outer surface of the lock bolt, 41, for causing shifting of said lock bolt into and out of locking position by the relative rotation of the spindle through its knob 39 when said tumblers have been adjusted with their slots in alignment to release said lock-bolt. The washer 57 is relatively small in diameter to reduce the frictional engagement with the end tumbler. Thus, after the tumblers have been set in combination by the actuating knob 18, the lock bolt may be freely shifted back and forth by the spindle knob 39 without danger of upsetting the combination. This construction is particularly desirable in locks of this general character as it will normally prevent inadvertently locking the bolt when the door is open by mere accidental turning of the knob or jarring of the door.

We claim:

1. In a lock of the character described, the combination with a casing and a mounting member therefor, of a rotatable tumbler actuating knob projecting outwardly from

the casing and beyond said mounting member, a graduated dial plate mounted concentrically of the axis of rotation of the knob, and an escutcheon plate secured to said 5 mounting member and adapted to normally maintain said dial in a fixed position, said escutcheon plate and dial plate having interengaging features for detachably securing said dial plate in a plurality of positions of 10 rotative adjustment with respect to said axis for varying the combination of the lock.

2. In a lock of the character described, the combination with a closure having a closure member and a lock casing secured thereto, of 15 a tumbler actuating knob projecting from the casing and accessible from the exterior of the closure member, a graduated dial plate disposed concentrically about the axis of rotation of said knob, an escutcheon plate for retaining the dial plate in central position, said 20 escutcheon plate and dial plate having interengaging features for detachably securing the dial plate in a plurality of positions of rotative adjustment with respect to said axis, 25 and means for securing the escutcheon plate to the closure member, accessible from the inner side of said closure member.

3. In the combination defined in claim 2, said interengaging features comprising radially extending grooves formed around the 30 peripheral edge of the dial plate, and a node formed on the inner surface of the escutcheon plate, cooperating with any selected one of said grooves for preventing rotational movement 35 of the dial plate.

4. In a lock of the character described, the combination with a closure having a closure member and a lock casing secured to said member, of a tumbler actuating knob extending 40 from the casing and accessible from the outside of the closure member, a graduated dial mounted concentrically of the axis of rotation of the knob, an escutcheon plate secured to said closure member and overlapping 45 the outer peripheral edge of the dial plate for holding the latter captive, and an indicator including an annular flange disposed between the dial plate and the closure member for securing the indicator in position, 50 and having a pointer overlapping the face of the dial plate.

5. In a lock of the character described, the combination with a closure having a closure member and a lock casing secured to said member, of a tumbler actuating knob extending 55 from the casing and accessible from the outside of the closure member, a graduated dial mounted concentrically of the axis of rotation of the knob, an escutcheon plate secured to said closure member and overlapping the outer peripheral edge of the dial plate for holding the latter captive, and an indicator including an annular flange disposed between the dial plate and the closure 60 member for securing the indicator in position,

tion, and having a pointer overlapping the face of the dial plate, said indicator and knob having interengaging features whereby said indicator is rotatable with the knob.

6. In the combination defined in claim 5, 70 said interengaging features including an inwardly extending tongue on said indicator flange engaged with a longitudinal groove formed in said knob.
